UNITED STATES PATENT OFFICE.

GUSTAV ADOLF UNTERBERG, OF KARLSRUHE-MÜHLBURG, GERMANY.

CONTACT-BREAKER.

No. 893,822.

Specification of Letters Patent.

Patented July 21, 1908.

Application filed April 16, 1907. Serial No. 368,609.

To all whom it may concern:

Be it known that I, GUSTAV ADOLF UNTERBERG, a citizen of the German Empire, and resident of Karlsruhe-Mühlburg, Baden, German Empire, have invented new and useful Improvements in Contact-Breakers, of which the following is a description.

The present invention relates to contact breakers for electrical igniting devices and the object is to construct the contact breaker so that it may easily be taken out of the machine and replaced, in case of defect, or for examination or for any other reason, without having to disconnect the operating lever system, or any other parts of the machine.

In order to render the present specification easily intelligible reference is had to the accompanying drawing in which similar letters of reference denote similar parts throughout the several views:—

Figure 1 is a longitudinal section through the device, Fig. 2 a cross section on line A—A of Fig. 1. Fig. 3 a plan view partly in section and Fig. 4 is an interior view of the cap and the mechanism mounted therein.

The contact breaker, consisting of the fixed member *a* and the double arm lever *b* *b'* is mounted in the cap *c*, which latter fits into the ring *d* with its annular flange *c'*, and may be fixed therein by means of a screw *e*. Thus the contact breaker will be turned together with the ring *d* by means of the known

lever system, which operates the arm *d'*. The contact is operated by means of the cam ring *h*, which is attached to the armature 35 shaft *g* by means of the disk *f*, the said cam ring operating the pin *b''* of the lever arm *b'*. Thus it will be seen that it is possible to remove the contact breaker from the machine by simply releasing the screw *e* and taking 40 off the cap *c*.

In addition to the other advantages, the device has the further advantage that by loosening the screw *e* the contact breaker can be easily adjusted as regards the cam ring *h*, 45 thus rendering possible a most accurate adjustment of the moment of ignition. The commencement of the interruption may be clearly seen through the window *c''* in the cap *c*. 50

I claim as my invention:—

In a contact breaking device for igniting mechanisms, a stationary and a movable member, means for operating the movable member periodically, and a detachable cap in 55 which the two contact breaking and making members are mounted.

In testimony whereof I affix my signature in the presence of two witnesses.

GUSTAV ADOLF UNTERBERG.
